UNITED STATES PATENT OFFICE.

WILLIAM B. MASON, OF BOSTON, MASSACHUSETTS, ASSIGNOR TO THE MASON
REGULATOR COMPANY, OF SAME PLACE.

GOVERNOR FOR STEAM-PUMPS.

SPECIFICATION forming part of Letters Patent No. 603,026, dated April 26, 1898.

Application filed July 7, 1897. Serial No. 643,695. (No model.)

To all whom it may concern:

Be it known that I, WILLIAM B. MASON, a citizen of the United States, residing at Boston, in the county of Suffolk and State of Massachusetts, have invented certain new and useful Improvements in Governors for Steam-Pumps, &c., of which the following is a specification, reference being had therein to the accompanying drawings.

10 The invention is in the nature of an improvement upon the governor for which United States Letters Patent No. 312,137 were granted to me February 10, 1885.

15 The present invention relates to governors of that class in which the throttle-valve or other controlling-valve of the pipe conveying the steam-supply or other medium of fluid-pressure is operated from a piston, the latter being acted upon by a liquid which is forced 20 into the pressure-chamber containing the said piston by means of a small pump that is connected with and operated from some moving part of the steam-pump, engine, or the like, which is to be controlled in its speed of working, the said valve thereby being operated in 25 such manner as to govern the supply of steam or other medium of fluid-pressure aforesaid.

25 The invention has reference more particularly to the piston aforesaid, the pressure-chamber within which the said piston is arranged, and the dash-pot or cushioning contrivance by means of which steadiness of movement of the piston and weight-lever are secured and undesirable oscillations are obviated.

35 The invention will be described first with reference to the accompanying drawings, in which is illustrated the best embodiment thereof that I have yet contrived, and afterward the distinguishing characteristics of the invention will be particularly pointed out and distinctly defined in the claims at the close of this specification.

40 Some of the parts which are shown in the accompanying drawings resemble those which are presented and described in the Letters Patent aforesaid, to which reference may be made for a fuller understanding thereof.

45 Figure 1 of the drawings is a view chiefly in transverse central section of the governor embodying my present invention. Fig. 2 is a view in plan of the shell or body of the gov-

ernor. Fig. 3 is a view showing certain parts of the governor in vertical section on the dotted line 3 3 of Fig. 2. Fig. 4 is a view 55 showing certain parts of the governor in vertical section on the dotted line 4 4 of Fig. 2.

13 is the shell or body of the governor, to which my present invention is shown applied. 25 is the bottom plate thereof, the said body 60 or shell and bottom plate being held together by means of screws 27. 9 is the bonnet or cover, which is fitted to the upper end of the said shell or body and secured thereto by screws 26, the said bonnet or cover having an 65 upwardly-extending hub to which is fitted the ring-shaped lower end of a bracket 8, the said bracket being adjustable around the said hub and secured in a fixed position thereon by means of the nut 7, which is turned onto 70 the threaded upper end of the said hub, and the said bracket 8 having mounted thereon pivotally at 4 the weight-lever 3, the latter having the weight 5 secured in the desired position of adjustment upon its horizontal 75 arm by means of the clamping-screw 6, and having connected pivotally to its vertical arm at 2 the coupling-piece 1, which is intended to have applied thereto one end of the rod (not shown) that forms part of the connections to the throttle or other valve which is to be operated. The said bonnet or cover 9 and its hub are centrally bored, as shown, to receive the rod 101 of the piston 10, the upper end of the said piston-rod supporting the 80 horizontal arm of the weight-lever 3.

85 D is the central or interior cavity holding the oil or other fluid which is employed within the governor.

90 21 is a rock-shaft which in practice is connected with and operated from some suitable moving part of the steam pump, engine, or the like which is to be controlled in its working. 20 is the usual forked arm, which is applied to the said rock-shaft 21. 23 is the 95 yoke, which is connected pivotally with the said forked arm by means of screws 22, and 24 is the pin or the like device by means of which the said yoke is joined to the plunger 19, so that as the rock-shaft 21 is operated 100 motion shall be communicated to the plunger 19 through the parts and connections which have been described.

E E' are the chambers in which the oppo-

site ends of the plunger 19 operate, and 18 designates the removable caps or covers in which the said chambers are partly formed. 5 F F are passages leading to the chambers E E', and F² F² are check-valves interposed between the said chambers and the interior cavity D on the supply side of the said chambers. G G' are passages leading from the said chambers to the pressure-chamber B, and 10 G² G² designate check-valves interposed between the chambers E E' and the pressure-chamber B.

J is a passage-way through which the oil or other fluid that has been pumped into the 15 pressure-chamber B is allowed to return to the chamber D, 14 being a needle-valve or the like regulating device by means of which to determine the rate at which the oil or other fluid shall be permitted to flow back into the 20 chamber D.

The foregoing parts, with the exception of the pressure-chamber B, are or may be as heretofore constructed in practice or as in the patent aforesaid, or may be of any other suitable construction and arrangement. The 25 piston 10 is formed hollow—that is to say, as a short hollow cylinder—it having one end thereof closed by a disk to which is applied the piston-rod 101 aforesaid. The flange or 30 annular portion of the piston fits into the space between the inner surface of the shell or body 13 and the periphery of the cup 11, which latter is secured by screws 12 to the diaphragm 121 of the shell or body 13. This 35 space constitutes the pressure-chamber B. The upper portion of the said pressure-chamber is closed or substantially closed by the annular portion of the piston 10, which I have made in practice to fit with a close-working 40 fit between the inner surface of shell 13 and the outer surface of the upper part of cup 11; but preferably the lower portion of the said pressure-chamber is enlarged somewhat by reducing the external diameter of the cup 11, 45 as indicated in the drawings, thereby providing greater capacity for the reception of the oil or other fluid which is pumped through the passages G G'. The interior space C of the cup 11 constitutes the dash-pot chamber, 50 the said dash-pot chamber being inclosed by the hollow piston 10, the disk of which covers the said chamber. Communication is established between the said dash-pot chamber and the pressure-chamber by means of the 55 passage H, the latter being formed wholly in the fixed parts of the governor. In the drawings the said passage is shown extending downward through the bottom of the cup 11, through the diaphragm 121 into the block 60 122, which is provided on the underside of said diaphragm, outward within the said block,

and then upward through the diaphragm and the wall of cup 11, in which last it turns again outwardly and opens into pressure-chamber B.

29 is a needle-valve by means of which to 65 regulate the flow of the fluid through passage-way H, 28 being a screw which serves as a cover to the hole in which the said valve 29 is located.

A certain portion of the fluid which is 70 pumped into pressure-chamber B finds its way into the space which is contained within the cup 11 and hollow piston 10, filling both. The disk of the piston, it covering the cup 11, as aforesaid, coacts with the contents of said cup 75 and of the interior of the piston itself in steadyng the movements of the piston.

The construction which has just been described is simpler than that which has been adopted heretofore, is compact in arrangement, is less expensive to produce, and is more convenient in use.

I claim as my invention—

1. The improved pump-governor having the annular pressure-chamber, the central dash-pot chamber, the restricted passage-way between the said chambers and the hollow piston inclosing said dash-pot chamber, the disk of said piston coacting with the contents of the said dash-pot chamber and the annular 90 portion of said piston closing the said pressure-chamber, substantially as described.

2. The improved pump-governor having the annular pressure-chamber, the central dash-pot chamber, the restricted passage-way between the said chambers and the hollow piston, covering the said dash-pot chamber, co-acting with the contents of its own interior and of the said dash-pot chamber and also provided with the annular portion closing or 100 substantially closing the said pressure-chamber, substantially as described.

3. The improved pump-governor having the annular pressure-chamber, the central dash-pot chamber, a passage-way communicating 105 between the pressure-chamber and the dash-pot chamber and formed in the fixed parts, a regulating-valve applied to the said passage-way, and the hollow piston, inclosing the said dash-pot chamber, coacting with the contents 110 of its own interior and of the said dash-pot chamber and also provided with the annular portion closing or substantially closing the said pressure-chamber, substantially as described.

In testimony whereof I affix my signature in presence of two witnesses.

WILLIAM B. MASON.
